(57) **CLAIM**

The ornamental design for the curvilinear outlet cover, as shown and described.

DESCRIPTION

This application is related to U.S. Patent Application No. 29/205,036 filed May 7, 2004, entitled “Cylindrical Power Hub”.

FIG. 1 is a perspective view of a curvilinear outlet cover according to the present invention;

FIG. 2 is a front view of the outlet cover of FIG. 1;

FIG. 3 is a bottom view of the outlet cover of FIG. 1;

FIG. 4 is a left-side view of the outlet cover of FIG. 1;

FIG. 5 is a right-side view of the outlet cover of FIG. 1;

FIG. 6 is a rear view of the outlet cover of FIG. 1;

FIG. 7 is a top view of the outlet cover of FIG. 1; and,

FIG. 8 is an environmental front view of an intended use for the outlet cover of FIG. 1.

The broken lines in FIGS. 1 through 8 are for illustrative purposes only and form no part of the claimed design.
